US00D668627S

(12) **United States Design Patent**
Chung

(10) **Patent No.:** **US D668,627 S**
(45) **Date of Patent:** **** Oct. 9, 2012**

(54) **MOBILE PHONE**

(75) Inventor: **Jae-Woong Chung**, Seongnam-si (KR)

(73) Assignee: **Samsung Electronics Co., Ltd. (KR)**

(**) Term: **14 Years**

(21) Appl. No.: **29/406,257**

(22) Filed: **Nov. 11, 2011**

(30) **Foreign Application Priority Data**

Jul. 29, 2011 (KR) 30-2011-0031690

(51) **LOC (9) Cl.** **14-03**

(52) **U.S. Cl.** ..... **D14/138 G**

(58) **Field of Classification Search** ..... D14/138 AD,
D14/138 G, 138 R, 138 AC, 138 C, 496,
D14/341, 345, 346, 203.7, 203.1, 203.3, 203.4,
D14/248; 455/575.1, 556.2, 556.1, 575.4,
455/575.3; D10/65, 78, 104
